Primary Examiner—Doris V. Coles*Assistant Examiner*—Mimosa De(74) *Attorney, Agent, or Firm*—Lawrence N. Ginsberg(57) **CLAIM**

The ornamental design for a multi-positional chair, as shown and described.

DESCRIPTION

FIG. 1 is a top, front perspective view of a first embodiment of the multi-positional chair;

FIG. 2 is a bottom, rear perspective view thereof;

FIG. 3 is a side elevational view thereof;

FIG. 4 is a top, front perspective view of a second embodiment of the multi-positional chair; and,

FIG. 5 is a bottom, rear perspective view thereof.

The side elevational view of the second embodiment, not shown, is the same as the side elevational view shown for the first embodiment.
